Primary Examiner — Darlington Ly*Assistant Examiner* — Giang Hoang Tran(74) *Attorney, Agent, or Firm* — FIDELI LAW PLLC;
Qiang Li(57) **CLAIM**

The ornamental design for an electric bicycle as shown.

DESCRIPTION

FIG. 1 is a top, front and left side perspective view of an electric bicycle showing our new design;

FIG. 2 is a bottom, rear and right side perspective view thereof;

FIG. 3 is a front and right side perspective view thereof;

FIG. 4 is a rear and left side perspective view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a top plan view thereof; and,

FIG. 10 is a bottom plan view thereof.

1 Claim, 10 Drawing Sheets(56)
